UNITED STATES PATENT OFFICE

154,664

DESIGN FOR A BOOKCASE

George E. Curneal, San Francisco, Calif.

Application April 18, 1947, Serial No. 138,476

Term of patent 7 years

(Cl. D33—19)

To all whom it may concern:

Be it known that I, George E. Curneal, a citizen of the United States, residing at San Francisco, in the county of San Francisco and State of California, have invented a new, original, and ornamental Design for a Book Case, of which the following is a specification, reference being had to the accompanying drawing, forming part thereof.

Figure 1 is a front perspective view of a book case, showing my new design, and

Figure 2 is a rear perspective view of the same.
I claim:

The ornamental design for a book case, as shown.

GEORGE E. CURNEAL.
